(57) **CLAIM**

The ornamental design for a lighting fixture assembly connector arm, as shown and described.

DESCRIPTION

FIG. 1 is a bottom perspective view of a lighting fixture assembly arm in accordance with our new design;

FIG. 2 is an enlarged top perspective view thereof;

FIG. 3 is an enlarged top plan view thereof;

FIG. 4 is an enlarged right side elevational view thereof; and,

FIG. 5 is an enlarged left side elevational view thereof.

The broken line showing of a portion of two lighting fixture housings and a suspension cable in FIG. 1 is for illustrative purposes only and forms no part of our claimed design.

The broken lines immediately adjacent the shaded areas in FIGS. 2 and 3 represent the bounds of the claim and all other broken lines are for illustrative purposes only. None of the broken lines form part of our claimed design.
